ABSTRACT: A dispatching control for elevators in which traffic is measured in terms of door open time for cars traveling between the terminals. The door open time of up traveling cars is balanced against the door open time of down traveling cars for a comparison time interval, and, if there is an unbalance of door open time, the terminal time at one terminal is adjusted to maintain substantially even car spacing.

ELEVATOR SYSTEM

This is a continuation of application Ser. No. 265,239 filed Mar. 14, 1963, now abandoned.

This invention relates to an automatic elevator system, and in particular it relates to a control system for operatorless elevators which shifts automatically between various modes of operation in accordance with traffic demands upon the system and the internal condition of the system.

Much of the developmental work in the elevator industry in recent years has been directed to improved automatic elevator control systems for the purpose of making the systems more directly responsive to the demands for service placed upon them. The present invention is directed to improved control apparatus for providing optimum service during periods of off-peak and down-peak operation, and also for providing controls which automatically shift the system to an off-hours program, and out of the off-hours program, in accordance with demands upon the system.

In accordance with the present invention, the system is always on an offpeak program if the traffic demands on the system are not such as to cause it to go into an up-peak, a down-peak, or an off-hours program. Certain traffic conditions automatically transfer the system from offpeak to down-peak, as will be described in more detail hereinafter; while absence of any demand for service for a predetermined period of time automatically shifts the system to an off-hours program. In addition, provision is made for an "emergency" program in the event there is a failure of the normal means used to cause elevators to serve passengers at the various floors of the building served by the system.

In the customary, or offpeak mode of service, a "normal terminal time" is established for departure of elevator cars from the bottom and top terminals served by the elevators. This is the time which ordinarily elapses from the selection of a car for dispatching from a particular terminal and the departure of the selected car from that terminal. Preferably a car is selected for dispatching only when there is a call for service. The normal terminal time at either terminal may be reduced in two different respects in response to certain demand conditions upon the system.

First, the dispatching interval is subject to modification dependent upon the ratio of building traffic in one direction to building traffic in the opposite direction. The ratio of traffic in the two directions is determined by accumulating the total time that elevator doors are open at intermediate floors for up traveling cars and for down traveling cars, during a given interval of time, and modifying the dispatching interval at one of the two terminals in accordance with the excess of accumulated door open time in one direction as against that in the opposite direction, the modification tending to restore imbalanced service in the two directions. If the cumulative door open time of up traveling cars exceeds that of down traveling cars the dispatching interval at the top terminal is shortened, and the amount by which it is shortened depends upon the extent of the difference between the up traveling cumulative door open time and the down travel cumulative door open time. Conversely, if the cumulative door open time of down traveling cars is greater than that of up traveling cars, the dispatching interval at the bottom is shortened.

Second, if the total amount of building traffic, as measured by the total quantity of up and down hall calls in simultaneous registration, exceeds a predetermined amount the terminal time at both terminals is reduced to a predetermined percentage of the normal terminal time. Conveniently, the reduction in terminal time based upon total building traffic shortens the terminal time to about 50 per cent of normal.

The first basis for modifying terminal time—i.e., the cumulative door open time ratio—continues to vary the dispatching interval at one or the other of the two terminals even when the normal terminal time has been reduced to one-half normal. The various possible terminal times will be hereinafter designated as follows:

1. The basic dispatch interval effective during the offpeak program is "normal terminal time"
2. The reduced dispatching interval based upon total building traffic will be referred to as "reduced terminal time."
3. The reduction in either normal terminal time or reduced terminal time dependent upon the ratio of building traffic in opposite directions will be referred to as "unbalanced terminal time."

It is apparent from the foregoing general description of the offpeak mode of operation of the elevator system that the system automatically accommodates itself to serve a high total volume of building traffic in both directions, and also accommodates itself automatically to any imbalance between traffic in the up direction and traffic in the down direction.

Comparison of cumulative door open time of cars traveling in the two directions requires that a comparison interval be established, and this interval is continuously recycled throughout the offpeak program. Conveniently, the door open times in the two directions may be accumulated for a comparison interval of 90 seconds, and at the end of that time the terminal time at one terminal or the other is adjusted in accordance with the imbalance between the cumulative door open times at the end of the comparison interval. If there is no imbalance the two terminal times remain equal, either at the normal time or at the reduced terminal time. Assuming that an unbalanced door open time is established at the end of a first comparison interval, the unbalanced door open time remains in effect throughout the second comparison interval, and is then either retained or corrected in accordance with conditions at the end of the second interval, and so forth.

Likewise, the system requires that an interval be established for recording door open time, and this is afforded by periodic pulses which are emitted from the time the door starts to open until it is fully closed. Thus, for example, if a door of an up traveling car remains open for 3 seconds it results in one pulse of the up car door open timer.

Selection of a proper comparison interval depends upon the number of elevators in a system, the number of floors in a building, the typical traffic patterns at different times of day, and other factors. Thus, the comparison interval is independently adjustable to permit the system to be modified, or "tuned" in accordance with experience during the early stages of usage of the system.

Similarly, the pulse interval for counting up door open time and down door open time may be adjusted so as to coordinate the pulse rate with the comparison interval.

Turning now to the down-peak mode of operation, a down-peak condition is considered to be in effect whenever any particular elevator car bypasses down hall calls on two successive trips by reason of being loaded. For convenience such a bypassed hall call may be referred to as a "load bypassed hall call."

Assuming the No. 1 car in the system load bypasses a down hall call on a first trip, and also load bypasses the same down hall call on the next succeeding trip, all load bypassed hall calls are established as preferred calls. The preferred calls may, of course, be answered by any available down traveling car—i.e., any car which is not set to load bypass such call. If the No. 1 car in the system arrives at the first floor on the second of the above described consecutive trips, and at least one preferred service down hall call is in registration, the No. 1 car will then be selected for preferred service operation.

When a car is selected for preferred service operation, the following events occur:

1. Assuming that the system is a two car system, the second car will reverse at its highest call and return for immediate dispatch from the first floor.
2. In such a two car system, the second car will also cause any down hall call which it load bypasses to be established as a preferred call.
3. The preferred service car (i.e., the first car in this example) will be dispatched promptly from the bottom terminal.

4. The preferred service car will reverse at the highest preferred call and serve only preferred calls below it until it becomes loaded, or until no further preferred calls are below it, at which time it will answer all down hall calls below it until it does become loaded. It will remain as a preferred service car until all preferred calls are served.

5. Only load bypassing of a down hall call by the selected preferred service car will establish that hall call as a preferred call—i.e., a down service call registered after the establishment of preferred service does not become a preferred call merely because it is bypassed by the preferred service car, since the latter is conditioned to answer only preferred calls.

The establishment and termination of off-hours service also is dependent upon the demand for service upon the system. Initiation of the off-hours program occurs, in general when there has been no demand for service on the system for a predetermined period of time. When any car has been idle for 6 minutes (or any other selected time period), herein called "shut down time," the motor generator set for that car is automatically shut down. When the motor generator sets of all cars are shut down, the system is automatically put on off-hours operation.

Assuming a two car system, the off-hours program is initiated when the second car shuts down its motor generator set. During offpeak operation of a two car system, one car ordinarily parks at the bottom terminal and one at the top terminal, each with its doors open, and a car is dispatched from either terminal only when there is a registered car call or hall call to be served by travel of the car toward the opposite terminal. When the shutdown time for the second car has expired, the car parked at the top terminal closes its doors and immediately starts to the bottom terminal, stopping to serve any registered down hall calls and car calls on the downward trip. The car parked at the bottom terminal remains there.

As the descending car arrives at the first floor its doors open to permit any passengers to depart; but no signals are actuated to indicate that the car is available for an up trip, the doors reclose, and the motor generator set shuts down as soon as the doors are fully closed. The car may respond to car calls registered by a passenger who happens to enter as the car arrives at the first floor; but otherwise the car remains as a standby throughout the off-hours program. All building traffic is handled by the other, or operating car, which remains with its motor generator set shut down but with its doors open so that any passenger approaching to go up will enter that car and press the car call button for the desired floor. This immediately starts the motor generator set, and after a set "door open time" the doors close and the car departs, answers all car calls and hall calls, returns to the bottom terminal and reopens its doors. After expiration of the shutdown time, the motor generator set again shuts down.

The off-hours program may terminate to return the standby car to service in response to any one of three conditions:

- An off-hours timer begins to run each time the operating car leaves the bottom terminal, and is reset each time said car arrives back at said terminal. If the timer times out before the car returns to the bottom terminal, the off-hours program terminates. The timer may conveniently be set to permit the operating car to make a full round trip with a single stop in either direction, or such other predetermined time as suits the particular system and building.
- Registration of a bottom terminal call, while the operating car is away from said terminal, conditions the off-hours timer to time out at an expedited rate which may be less than half the usual period required—i.e., 25 seconds if the timer ordinarily times out in two minutes; and off-hours program terminates.
- Load sensing means in the operating car conditions it to bypass hall calls if the load exceeds a maximum, and if this occurs the off-hours program terminates immediately.

Emergency service is provided in the present system when, for example, there is a voltage supply failure to the hall call relays. Prior systems for providing emergency service have utilized means for registering false hall calls which would cause one car or another in the system to stop at every floor until the voltage supply to the hall call circuits was restored.

The present system includes an improved means for establishing emergency service which does not require the registration of false car calls.

10 The controller includes an emergency lane for each car having contacts which are energized when supply of voltage to the hall call relays fails. Such a controller lane is provided for each car in the system, and if all cars are in service the floors of the building are divided equally between the various cars so that each car stops at predetermined floors on any down trip during the continuance of the emergency condition. Thus, for example, in a two car system, one of the two cars may serve all odd numbered floors and the other car will serve all even

15 number of floors. The energized contacts in each emergency program lane of the controller cooperate with the usual traveling controller contacts to cause the car to stop at the floor corresponding to the energized emergency program lane contact. If one car is out of service, all emergency program contacts on the in-service car are energized so that the one car stops at all floors on each down trip.

20 Further features and advantages of the invention will readily be apparent from the following specification and from the drawings, in which:

25 FIG. 1 is a diagrammatic illustration of an elevator which may be one of a multiple car elevator system;

FIGS. 2 and 2a are an across-the-line circuit diagram, partially diagrammatic, of circuitry associated with each car of the system;

30 FIGS. 3, 3a and 3b are an across-the-line diagram of control circuitry common to the two cars;

FIG. 4 is an across-the-line diagram of a portion of the hall call circuitry; and

35 FIG. 5 is an across-the-line diagram of a portion of the control circuitry associated with off hours or low demand operation; and

40 FIGS. 2', 2a' and 3' and 3a', 3b', 4' and, 5' are keys for the corresponding across-the-line diagrams.

45 The detailed disclosure contained herein is limited for the most part to the novel circuitry of the invention. Detailed information on door operation, car speed controls, leveling and safety circuits, for example, are not shown. Any suitable control for providing the desired functions may be used.

50 Turning now to the drawings, FIG. 1 illustrates in diagrammatic form a single car 10 of an elevator installation. Car 10 is movable through a shaft 11 between a lower terminal floor 12 and an upper terminal floor 13. Intermediate floor 14 is representative of the several intermediate levels in the building which may be serviced by the elevator. Movement of car 10 is effected by a variable speed motor 15 energized from a motor generator set 16. Motor 16a is preferably energized from a suitable three phase source (not shown) through a controller 17.

55 60 Elevator car 10 has a door 18 actuated by a suitable control mechanism 19.

The subsequent description contemplates an elevator system having two cars which travel between the lower and upper terminals serving a plurality of intermediate floors.

65 65 Many of the novel features of the invention may be extended to systems incorporating three or more cars and to installations in which floors below the lower terminal, as basements, and above an upper terminal, as a penthouse, may be served.

The system has the normal or "offpeak" mode of operation 70 in which one car will park at the lower terminal and the other at the upper terminal, each with its doors open and ready to receive passengers. The car at the lower terminal will be dispatched only if there is a demand for service, as a car call from a passenger entering the car at the terminal or an up hall call, or if the top terminal parking requirement is not filled or

about to be filled by an up traveling car. Similarly, the car at the upper terminal will be dispatched to answer a car call, a down hall call or to fulfill the lower terminal parking requirement. Dispatching interval timers at each terminal control the period of time a car must wait at a terminal before leaving for the other terminal or to answer a call.

In the following discussion the two cars of the system will be designated "a" and "b"; and certain components individual to the cars will be indicated by the appropriate suffix "a" or "b", where such indication will aid in an understanding of the operation of the system. In some cases, contacts are shown for relays which are not illustrated. The conditions under which these relays are energized will be described, although the circuits for them may not form an essential element of the invention.

Turning now to FIG. 2 of the drawings, a portion of the control circuits for one car is illustrated. Lines 20 and 21 are connected with a source of operating potential, as 110 v. AC. Block 22 represents suitable car running, leveling and door operator controls, the details of which form no portion of the invention. Certain elements of these controls are illustrated within box 22, as an aid to an understanding of other operations of the control circuitry.

A car at a terminal will be conditioned to run by energization of signal-for-up-direction or signal-for-down-direction relays SUA and SDA, each of which has a contact in the circuitry of the car running controls 22. When the car is parked at the lower or upper terminal, during off peak or normal operation, neither relay SUA nor SDA is energized.

The operation of the circuits for dispatching a car upwardly from the lower terminal will be considered first. The energization circuit of signal-for-up-direction relay SUA includes contact SDA-2 which is closed except when the car has been selected for down operation (as to a basement), contact NU-*al* of the next-up relay NU-*a*, which will be closed as described below, contact NUT, associated with the next-up timer NUT, contact CU-1 associated with the up call relay, closed when an up call is registered, and contact UTZ-1, closed except when the car *a* is at the upper terminal. A holding circuit for relay SUA is completed through contact SUA-2 maintaining the signal for up direction once it has been established, until the car reaches the upper terminal and contact UTZ-1 opens.

Next up relay NU-*a* has an energizing circuit including contacts PL which are closed when the car is at the lower terminal and in service, normally closed contact OH-4 associated with the off hours relay OH and contact NU-*bl* associated with the NU-*b* relay for the car *b*. Whenever car *a* arrives at the lower terminal and is in service, assuming that off-hours operation is not in effect, and that the other car, *b*, has not been selected for up operation, relay NU-*a* is energized. In the circuitry for car *b*, a similar circuit for relay NU-*b* (not shown) is interlocked with relay NU-*a*.

Turning now to the common signal schematic, FIG. 3, which shows circuits common to all cars, the basic operation for the lower terminal dispatching interval timer NUT will be described. The lines 25 and 26 are connected with a suitable source of power, as 110 volts AC. Timer NUT, connected across the line includes an electronic timing circuit and a relay NUT which is energized on expiration of the timing period. The details of operation of the circuit are not necessary to an understanding of the system operation. An enabling circuit for the timer is connected between terminals 28 and 29 and must be completed before the timing period starts. The dispatching interval may be reduced by changing the resistance across terminals 30 and 31, in a circuit with the internal resistance of the timer (not shown).

The operation of timer NUT is initiated by closing of either contact NU-*a*2 or NU-*b*2 to complete the circuit between terminals 28 and 29. Contact OH2 is closed in off-peak operation. It will be recalled that relay NU-*a* or NU-*b* closes when the respective car is at the lower terminal, available for dispatch and the other car has not already been selected as

next to be dispatched in the up direction. A suitable dispatching interval, as 15 seconds, may be selected for the usual operation of the timer. At the end of the timing period, contact NUT closes, in the circuit of relay SUA (FIG. 2). If there is no up call registered, relay SUA is not energized and the car is not dispatched. Upon registration of a service call closing contact CU-1, or if CU-1 is closed when NUT closes, relay SUA is energized, closing contact SUA-1 in the car controller 22 and initiating operation of the door operator and car running circuitry. The car leaves the lower terminal to answer registered car calls and up hall calls, proceeding to the upper terminal.

The down car selection and dispatch circuitry is similar and will be described only briefly. Signal for down direction relay SDA (FIG. 2b) is energized through interlock contact SUA-3, next down relay contact ND-*al*, down dispatch timer contact NDT, down call contact CD-1 and contact LTZ-*al*, indicating that the car is not at the lower terminal. A holding circuit is completed upon energization of relay SDA through contacts SUA-3, SDA-3 and LTZ-*al*.

Next down signal relay ND-*a* has an energizing circuit including contact PT which closes when the car *a* is at the upper terminal, and an interlock with relay ND-*bl*, preventing the car *a* from being selected at a time when car *b* has already been selected. The upper terminal dispatching interval timer NDT is identical with the timer NUT. It is energized by connection between lines 25 and 26 and operation is initiated upon completion of the circuit between terminals 35 and 36, 30 upon closure of either contact ND-*a*3 or ND-*b*2, the next down signal relays for the two cars. The basic timing interval, as 15 seconds, for the timer NDT may be varied by changing the resistance across terminals 37 and 38. Upon closure of contact NDT, relay SDA is energized, closing contact SDA-1 in the control circuitry 22 initiating the closure of the doors and downward movement of the car.

In accordance with the present invention, the period of operation of the timers NUT and NDT is varied as a function of the demand for service in the system. More particularly, the dispatch interval times are varied in accordance with the difference between the door open time for up traveling cars and the door open time for down traveling cars. Information regarding the door open times is accumulated for a predetermined period, as 90 seconds, and then utilized to modify the operation of the appropriate dispatch timer. For example, if the door open time for up traveling cars exceeds the door open time for down traveling cars during the measuring period, the dispatching interval at the upper terminal is reduced while that of the lower terminal remains unchanged. Similarly, if the door open time for down travel cars exceeds that of up traveling cars, the dispatch interval at the lower terminal is reduced. This reduces the tendency of a car whose doors are open for an extended period during travel between the terminals to lag behind the other car in being dispatched from the terminals. In addition, the overall traffic in the system is measured and when it exceeds a predetermined quantity, both dispatch intervals are reduced by a predetermined factor, as one-half.

The operating time for the terminal dispatching interval timers NUT and NDT is reduced by introducing resistance between terminals 30 and 31 of timer NUT or terminals 37 and 38 of timer NDT. Associated with timer NUT are two step switch sections STP1-3 and STP2-3 connected to terminals 30 and 31 through contacts STSR-1 and STSL-1 of the right and left step switch relays STSR and STSL, respectively. These relays are energized alternately, as will appear, to connect one or the other of the step switch sections STP1-3 and STP2-3 with the timer. The circuitry for operating the step switch sections will be discussed below. For present purposes it is sufficient to understand that the movable contacts of the switches will be displaced from the center or home position, in which they are shown, in a counterclockwise direction if the door open time for down traveling cars exceeds the door open time of up traveling cars, while displacement will be in the

clockwise direction if the door open time of up traveling cars exceeds that of down traveling cars. Each of the step switches has 12 positions in each direction from the home position. Connected between the terminals located in a counterclockwise direction from the home position of switch STP1-3 are series of resistors 39. When switch STP1-3 is in its home position or any position to the right thereof, all of the resistance is connected in the circuit. The total resistance is a portion of the circuitry which establishes the basic 15 second operating time of timer NUT. As the movable contact of switch STP1-3 moves in a counterclockwise direction, the resistance connected across terminals 30-31 of timer NUT is reduced until at the end of travel of the movable arm, there is no resistance connected in the circuit and a short appears across terminals 30-31. This corresponds with a dispatch interval time of 0 seconds.

If the door open time of up traveling cars exceeds that of down traveling cars, the movable arm of step switches is displaced to the right of the home position and the timing interval of timer NUT is not reduced.

To minimize the number of physical resistors in the circuit, connections are made between terminals of step switch section STP2-3 and the corresponding terminals of switch section STP1-3. Accordingly, no matter which switch section is operative, it is the same resistors which are connected in the circuit.

Step switch sections STP1-2 and STP2-2 are connected with the upper terminal dispatch timer NDT and operate in a manner similar to the operation of step switch sections STP1-3 and STP2-3. One or the other of the switch sections is connected across terminals 37-38 or timer NDT through contacts STSR-2 and STSL-2. A surplus of door open time in the down direction has no effect on the timing of the dispatch interval at the upper terminal. However, if the door open time for up traveling cars exceeds that for down traveling cars, step switch STP1-2 or STP2-2 is displaced in the clockwise direction shorting a portion of resistors reducing the resistance connected across terminals 37-38 of timer NDT. Again, the number of physical resistors used is minimized by connecting appropriate terminals of switch section STP2-2 to corresponding terminals of STP1-2, as indicated in FIG. 3a.

During the time that one of the step switches is controlling the operation of timers NUT and NDT, as switch sections STP1, information regarding the relative door open times for the cars is accumulated by step switch STP2. At the end of the timing period, the operation is reversed with switch sections STP2 controlling the operation of timers NUT and NDT, and information being accumulated by step switch STP1. The circuitry which affects this operation will now be described in detail.

Each car is provided with a door switch (part of controls 22, FIG. 2), which closes when the door of the car is not fully closed, energizing relay DCL. This in turn closes contact DCL-1 (FIG. 2a). If car *a* is not at one of the terminals, both contacts UTZ-2 and LTZ-a2 are closed and one of the up or down door open signaling relays UX-a or DX-a, respectively is energized depending on the direction of travel of the car as indicated by the closure of contact SUA-4 for up travel or SDA-4 if the car is conditioned for travel in the down direction.

The up and down door timers UDT and DDT (FIG. 3a) provide a measure of the up and down door open time. Considering first up door timer UDT, the timer is conditioned for operation when the circuit between terminals 41 and 42 is completed. This is the situation when contacts OP-1 are closed indicating offpeak operation since contact TUDT, associated with the UDT timer reset circuit, is normally closed, as will appear. Timer UDT operates only when one or both of resistors 43 and 44 is connected between terminals 45, 46. Connected in series with resistor 43 is contact UX-a associated with the up door open signal relay UX-a for car *a* while resistor 44 is connected across terminals 45 and 46 through contact UX-b associated with the up door open signal

relay for car *b*. Thus, whenever a car conditioned for up travel is stopped with its doors in other than the fully closed position, one of resistors 43 or 44 is connected in the circuit of timer UDT. If both cars are moving in the up direction and are stopped with their doors in other than the fully closed position, both resistors 43 and 44 are connected in the circuit. The period of timer UDT is such that with one of resistors 43 or 44 connected in the circuit, it will time out in a period of 3 seconds. With both resistors connected in the circuit the timing period is 1½ seconds. As will appear, timer UDT is automatically recycled and the rate at which it times out, i.e. the rate of energization of relay UDT, provides a measure of the total door open time of up traveling cars.

Timer UDT is recycled in the following manner. Capacitor relay UDTR and relay TUDT are both normally energized and their respective contacts UDTR and TUDT are closed. When timer UDT times out energizing relay UDT, contact UDT-1 opens. Capacitor relay UDTR is immediately deenergized, opening its associated contact UDTR. Relay TUDT provides a slight delay in dropping out to permit relay UDT to be picked up for a short interval of time in order that the various contacts associated therewith will have an opportunity to perform their functions. When relay TUDT times out, contact TUDT associated therewith opens dropping out relay UDT, whereupon contact UDT-1 closes energizing capacitor timer UDTR which picks up after a slight delay. Following this delay, contact UDTR closes reenergizing relay TUDT and reestablishing the enabling circuit for UDT.

Down-door open timer DDT operates in a similar manner as up-door-open timer UDT. In offpeak operation, contact OP-2 is closed completing the timer actuation circuit between terminals 47 and 48 through reset contact TDGT. Any time a car conditioned for down travel is stopped and its doors are not fully closed, one or both contacts DX-a and DX-b is closed, connecting one or both resistors 49 and 50 across terminals 51, 52. The timing rate of timer DDT is the same as that for UDT, 3 seconds with one resistor in the circuit and 1½ seconds with both. The reset circuitry for timer DDT is identical with that for timer UDT and a specific illustration and description of it is not given. The rate of actuation of relay DDT provides a measure of the door open time of down traveling cars.

Interval timer IT provides a time base for the measurement of door-open time, controlling the period during which information is collected by the step switches. During offpeak operation, contact OP-3 is closed completing the actuating circuit of timer IT through closed contact TIT associated with a reset circuit for the timer. A suitable operating period for timer IT is 90 seconds. The reset circuit for timer IT is identical with that provided for timer UDT and a specific disclosure and description are not given.

Energization of relay IT at 90 second intervals closes contact IT momentarily energizing step switch relay STS. Relay STS is a single coil impulse latching relay similar in operation to a toggle switch. It has associated therewith two contacts STS-L and STS-R, one of which is closed at all times energizing the corresponding relay STSL or STSR. Upon each actuation of relay STS by timer IT, the condition of contacts STS-L and STS-R is reversed, reversing the condition of relays STSL and STSR and establishing which of the step switches STP1 and STP2 collects information or controls timers NUT and NDT.

For the purpose of the immediately following discussion, it will be assumed that contact STS-L is closed, energizing relay STSL. Considering now the actuating circuitry for step switch STP1 (FIG. 3b), it will be seen that contacts STSL-3 and STSL-4, associated with left step switch relay STSL, complete energizing circuits for step switch stepping coils STP1 (up) and STP1 (down), respectively. Included in the energizing circuits for these stepping coils are contacts UDT-2 and DDT-2, respectively, which are associated with the door open timers UDT and DDT. Upon each actuation or recycling of the door-open timers, an impulse is transmitted to the appropriate up or

down stepping coil. This causes a stepping motion of the movable arm of step switch STP1 in either the up or down direction.

During the time door-open information is transmitted to the step switch STP1, the timers NUT and NDT are under the control of step switch STP2 as contacts STSL-1 and STSL-2 (FIGS. 3 and 3a) are closed.

At the end of the period of timer IT, contact IT closes, pulsing relay STS and reversing the condition of contacts STSL and STSR. Contact STSR closes, energizing relay STSR while contact STS-L opens breaking the circuit for relay STSL. This results in disconnecting step switch sections STP2-2 and STP2-3 from timers NDT and NUT, and connecting step switch sections STP1-2 and STP1-3 thereto. Contacts STSL-3 and STSL-4 open, preventing the transfer of further door open information to step switch STP1 while contacts STSR-3 and STSR-4 close directing door open information to step switch STP2.

At the end of each 90 second period of timer IT, the step switch which has just finished controlling the operation of timer NUT and NDT is reset before further information is transmitted to it. On closure of contact IT, an energizing circuit is completed to capacity timer TSRS (FIG. 3a). This timer does not complete its cycle and actuate the contacts associated therewith for a period of approximately one-half second. This delay insures complete transfer of relays STSR and STSL. Relay ITS, in parallel with relay STS and timer TSRS, is energized on closure of contact IT, closing holding contacts ITS to a circuit including step switch homing relay contacts STPIH and STP2H. Upon completion of the period of timer TSRS, a circuit is completed through contact TSRS-1 and contact STSR-5 to the movable arm of step switch STP2-1 (FIG. 3b). Unless the movable arm of the switch is at the center or home position, the up-step coil STP2 (up) is energized through interrupter switch STP2. The interrupter switch opens and closes automatically providing impulses to the step coil moving the arm of switch STP2-1 in the clockwise direction until it reaches the home position (in which it is shown) at which time a circuit is completed through contacts TSRS-1 and STSR-5 energizing homing relay STP2H. Energization of this relay opens contact STP2H in the holding circuit for timer TSRS dropping it out, opening contact TSRS-1 and closing contact TSRS-2. This completes the homing operation and step switch STP2-1 is ready to accept further door-open information through the action of timers UDT and DDT, and contacts UDT-2 and DDT.

At the end of the next 90 second period of timer IT, the two stepping switches STP1 and STP2 will reverse their functions, with STP2 controlling the operation of timer NUT and NDT and STP1 again collecting information on door-open timers (after having been reset at the home position).

It will be noted that during the homing operation, contact TSRS-2 is opened, preventing the completion of the circuitry to the stepping coils through the door timer contacts UDT-2 and DDT.

Whenever the system is in other than the offpeak mode of operation, contacts OP-4 and OP-5 close causing both the step switches STP1 and STP2 to seek the home positions.

The timing period for timer IT must be selected to provide the proper corrective operation depending upon the nature of the elevator installation. If the installation is subject to rapid shifts in the nature of the service demand, the period of operation of timer IT should be relatively short. On the other hand, if the changes are more gradual, the period may be longer. The timing periods for timers UDT and DDT should be quite short as compared with the base time of timer IT.

The basic operating time of the terminal dispatch interval timers NUT and NDT may be varied in accordance with the total number of service calls registered in the system. A quota relay, QA (FIG. 3b) performs this function. Rectifier 60 provides a direct current operating potential, stabilized through a voltage regulator 61 for the relay QA. Relay QA is energized through a circuit including potentiometer 62 and normally

closed contact QA-1. A series of contacts n U and n D are provided, representing the up and down calls registered for each floor in the system, it being understood that there is a U-contact and D-contact for each floor corresponding to the hall calls which may be registered. When a sufficient number of n U or n D contacts is closed to effect energization of relay QA, contact QA-1 opens introducing potentiometer 63 into the circuit which may be adjusted to control the dropout point for relay QA. Contact QA-2 (FIG. 3) closes connecting resistor 64 across terminals 30 and 31 of timer NUT. This reduces the timing period by a predetermined factor, as one-half. For example, in a specific installation, timer NUT has a period of 15 seconds without resistor 64, but with all of the resistors associated with step switch STP1-3 in the circuit. The addition of resistor 64 reduces this time to 8 seconds. The step switches still continue to modify this time as required by the relative up and down door-open time of the cars. Similarly, contact QA-3 connects resistor 65 in the timing circuit of timer NDT when the predetermined number of calls is registered. During periods of up-peak operation, contact UPK is closed connecting resistor 64 in the circuit of the lower terminal dispatching interval timer NUT.

In the event of a failure in the voltage supply for the hall call pushbuttons, it is desirable to provide a means for conditioning one or both cars to stop at the various floors of the building to pick up passengers who may be waiting. It has in the past been proposed to accomplish this through the synthetic registration of service demands. This requires complex circuitry and necessitates the energization of a substantial number of relays. The present system provides for emergency service by conditioning the car or cars in operation for stopping at each or alternate floors, in a novel manner.

A portion of the hall call circuitry is shown in FIG. 4, obtaining its energization through lines 66 and 67, from a suitable source. When the lines are energized, relay CPF, connected thereacross, is energized, closing contacts CPF-1 and CPF-2 to the remainder of the circuit and opening contacts CPF-3 and CPF-4. Should the hall supply voltage fail, relay CPF drops out opening contacts CPF-1, CPF-2 and closing contacts CPF-3, CPF-4. An attempt is made to recover power for the hall call circuitry from the elevator cars. If voltage is available from car a , relay PFA is energized closing contacts PFA-1 and PFA-2, opening contacts PFA-3 and PFA-4. As contacts CPF-3 and CPF-4 are closed, voltage from the car a in the hall call circuit may be utilized. If voltage is not available from car a , relay PFA is dropped out with contacts PFA-1, PFA-2 open and contacts PFA-3, PFA-4 closed. This permits voltage which may be available from car b to energize the hall call circuitry. If, however, voltage is not available from either car, due to broken connections or to blown fuses 68, 69, relay CFF is not energized.

Contact CFF (FIG. 2a, below broken line 70) is closed completing an energization circuit for emergency relay 2EP. If both of the cars a and b are in service, only relay 2EP (for each car) will be energized. If, however, one of the cars is out of service, the interlock relay contact SS- b , for example, will be closed completing an energization circuit for relay 1EP- a . If car a is out of service, a similar relay 1EP- b is energized through interlock contact SS- a in the individual circuitry for car b . A portion of the car call circuitry is illustrated in FIG. 2a, below broken line 71. Before proceeding with a consideration of the emergency operation, a brief description of the normal operation will be given.

The circuitry for one floor, n , is shown. It will be understood that similar circuitry will be provided for each of the floors to be served. When a car call is registered as by pressing a pushbutton n in the car, relay n C is energized and contact n C closes completing a holding circuit. At the same time, an operating potential is applied to fixed segment n CC, a part of the car position mechanism. The brushes CC1 and CC2 are part of the car position mechanism and move relative to the fixed segment n CC in accordance with movement of the car. Depending upon the direction of the travel of the car, either

contact UA-1 or DA-1 will be closed, representing up or down movement of the car, respectively. Assuming that the car is traveling in the down direction with contact DA-1 closed, when brush CC2 contacts fixed segment *n* CC, car call relay CC is energized. Contacts (not shown) associated with relay CC and located in the car running control 22 bring the car to a stop at the appropriate floor to answer the call. Similarly, if the car is traveling in an up direction, the circuit to relay CC is completed through contact UA-1 and brush CC1. In practice, the circuit for the car call relay will generally be somewhat more complex, utilizing a plurality of brushes and controls to cancel the car call and reduce the speed of the car before it is stopped, should this be necessary.

Connected with brush CC2 is a brush CC2' which cooperates with a series of floor segments identified as M (mezzanine) 2, 3 . . . 12, 13 and 14. In the emergency mode of operation, segments representing the odd numbered floors M, 3 . . . and 13 will be connected with line 21 through contact 2EP-3. Thus, the car *a*, to which a portion of the circuitry of FIG. 2 applies, is conditioned to stop at the odd numbered floors M, 3 . . . and 13 during each downward trip, as in response to car calls for those floors. In the event the car becomes loaded, load switch 75 in car control 22 is closed energizing relay LS. Contact LS-1 opens breaking the energizing circuit for the emergency car call segments. Similar circuitry as shown conditions car *b* to stop at the even numbered floors.

In the event only car *a* is in service during the emergency program, relay 1EP-*a* is energized through contact SS-*b*. Contact 1EP-*a* completes a circuit to the other segments of the emergency system, corresponding with even numbered floors 2 . . . 12 and 14. In this condition of the system, the car *a* stops at each floor during its downward travel. In a like manner, car *b* is conditioned to stop at all floors if car *a* is not in service. In a system having more than two cars, the stopping arrangement may be divided up in any other suitable manner.

Contacts 2EP-1 and 2EP-2 of the emergency program relay are connected across the NUT and the NDT timer contacts in the circuits of relays SUA and SDA. Thus, during emergency operation there is no delay prior to car dispatch at the terminals.

Although a loaded car will bypass the predetermined stops set up under the emergency program, it will continue to respond to car calls which are registered within the car.

In many types of buildings, there is often a condition of heavy down travel during certain portions of the day. For example, in a hotel this may occur in the morning at about the breakfast hour, while in an office building it may occur at the lunch hour and again when the offices close in the evening. Cars dispatched downwardly from the upper terminal often become loaded before they reach the lower terminal and bypass hall calls at the lower floors. Low level hall calls may be unanswered for an extended period of time.

In accordance with a further aspect of the invention, preferred service is provided to floors where hall calls for down service are bypassed by a loaded car on two successive trips. During preferred service operation, one car is assigned to handle all preferred service calls, i.e. those calls which have been bypassed by a loaded car, and the assigned car answers only these calls until they have all been served. The other car continues to operate although on an accelerated program to answer other calls.

Turning now to FIG. 4, it will be seen that actuation of a representative hall call button as 10 down, energizes relay 10D which is held in through its associated contact 10D. With relay 10D energized, segment 10LWA in the LWA column and 10D in the LWB column of the car position mechanism, are connected with line 67. On the next down trip of one of the cars, if the car is not loaded, the call at the 10th floor is answered in a manner similar to that described above for the answering of car calls (the specific circuitry is not here shown). Upon answering the hall call, the call is cancelled and relay 10D drops out.

If the next down traveling car, *a*, is loaded to capacity, so that load switch 75 is closed and relay LS energized, the car cannot stop for the hall call. As the car passes the 10th floor, brush LWA contacts segment 10LWA and a circuit is completed energizing relay LP, assuming that contacts LPA-*b* and LPB-*b* are closed, as will be the case if the car *b* has not bypassed a hall call. Contact LS-2 is closed as the car is loaded and contact DA-4 is closed as the car is traveling in the down direction.

When relay LP is energized, contact LP closes completing an energization circuit for relay LPA through contact LPB-1, DPK-1 and 2EP-4. A holding circuit is completed through contact LPA-1 and contact UTZ-3 associated with the upper terminal zone relay. As car *a* reaches the lower terminal, contact LTZ-a3 closes completing a circuit through contact LPA-2 energizing relay LPB. Contact LPB-2 closes completing a holding circuit for relay LPB. Car *a* is dispatched from the lower terminal in the normal manner and as it leaves, contact LTZ-a4 closes. When car *a* reaches the upper terminal, contact UTZ-3 in the holding circuit for relay LPA opens, dropping out LPA and opening contacts LPA-1 and LPA-2. Relay LPB remains energized through contact LTZ-a4, LPB-2, DPK-1 and 2EP-4.

If during the next down trip for car *a*, there are no hall calls which are load bypassed, the calls are all answered and cancelled. When car *a* arrives at the lower terminal, contact LTZ-a4 opens, and relay LPB is dropped out.

Assuming on the other hand that car *a* is again loaded and a registered hall call is bypassed, such bypassed hall calls will be established as preferred service calls. Referring to the circuitry in the center of FIG. 4, it will be recalled that segment 10D in the LWB column of the car position mechanism is connected with line 67 when a hall call is registered. If a loaded car with its LPB relay energized bypasses a registered hall call, a circuit is completed from segment 10D, in the LWB column, through brush LWB1, contact LS-3 associated with the load switch relay, contact DA-3, contact LPB-3, brush LWB2 to segment 10LW in the LWB column. This circuit energizes relay 10DW, the preferred service relay for the tenth floor. The contact 10DW-1 closes completing a holding circuit for relay 10DW. Contact 10DW-2, in the circuit associated with relays DWA and DWB, opens. When car *a* reaches the lower terminal, relay DWB is energized through car position segment 1DW, brush DW and contact LPB-4. Relay DWA, however, is not energized, as contact 10DW-2 is open. Of course, any additional hall calls which have been bypassed will result in further open contacts in the DW column including 10DW-2.

With car *a* in the vicinity of the lower terminal, contact LTP1 is closed and the circuit is completed energizing the preferred service relay LN for car *a*. This circuit is completed through contact LPB-5, DWA (as the DWA relay is not energized), LN-bl (indicating that the preferred service relay for car *b* is not energized) and 2EP-5. Contact LN-1 completes a holding circuit for relay LN. Contact LN-2 closes energizing down-peak relay DPK, which is common to both cars. Contact LN-3 closes bypassing contact LPB-4 in the circuit to brush DW. The opening of down-peak contact DPK-1 prevents further energization of relays LPA or LPB of either car.

During subsequent operation, any hall call which is load bypassed by either car is established as a preferred service call as contact DPK-2 in a circuit between brushes LWB1 and LWB2 is closed (and a similar contact is closed in the circuitry for car *b*). Thus, whenever a car load bypasses a hall call, a circuit is completed through the load switch contact LS-3, the down direction contact DA-3 and contact DPK-2 between brushes LWB1 and LWB2 energizing the corresponding DW relay for the passed floor.

The car selected for preferred service operation by energization of its relay LN is then directed to respond solely to the hall calls registered on the DW relays while the other car responds to other calls in the system. The particular manner in which the preferred service is provided is not pertinent to the

present invention and is not disclosed in detail. It should be sufficient to consider that the normal hall call answering circuitry (responsive to calls registered on the DC column segments) for the car is disabled, as by opening a switch contact in the circuit, while preferred service circuitry is actuated to respond to the bypassed calls registered on the LW column segments.

When the demand for service is low, it is desirable to shut down the motor-generator sets 16 which power the elevator drive motors 15, in order to conserve power and reduce wear and tear on the motor-generator sets. It will be recalled that during normal operation, one car is located at the lower terminal and the other at the upper terminal, and the cars do not leave unless a call for service is registered or there is an unfilled parking requirement at the other terminal. Each car is provided with a timer TS which will effect a shut-down of the associated motor-generator set after a predetermined time at a terminal without a call for service.

The circuitry for one car, *a*, is illustrated in FIG. 5, together with appropriate portions of the circuit associated with car *b*. The circuit for car *b* is the same.

The timer TS-*a* is connected between power lines 76 and 77. When a circuit between terminals 78, 79 of the timer is completed, it will begin its timing cycle. The timer may have a period of several minutes, the exact time depending on the nature of the building being served. In one specific installation of two cars in a 15-story hotel, timer TS-*a* has a period of 6 minutes. The initiating circuit for the timer is completed through contact PA which when closed indicates that the car is not moving, and may be a part of the brake control circuitry, contact S-1, which when closed indicates there are no calls registered in the system and one of the terminal zone relay contacts UTZ-4 or LTZ-5. At the end of the timing period, contact TS-*a* opens breaking the holding circuit for relay TSA-*a* will be energized at any time there is a call registered to which this car should respond, contact S-2 being closed.

When both TS timers, TS-*a* associated with car *a* and TS-*b* (not shown) associated with car *b*, have timed out, so that both relays TSA-*a* and TSA-*b* (not shown) are deenergized, a circuit is completed energizing the off-hours service relay OHS-*a* for the car at the lower terminal. The energizing circuit is completed through contact NU-*a* (indicating that car *a* has been selected as next up at the lower terminal), contact TSA-*a*2, contact TSA-*b* and contact SS-*a*2 (indicating that car *a* is in service). A holding circuit for relay OHS-*a* is completely through contact OHS-*a*1, load switch contact LS-4 and contact TOH associated with the off-hours timer. The car for which relay OHS is energized is selected to supply off-hours service for the system. The OHS relay for each car has contacts (as OHS-*a*2 and OHS-*b*2) in the circuit of the off-hours relay OH common to both cars. Thus, no matter which car is selected to provide off-hours service (OHS energized), the OH relay common to both cars is energized. The car at the upper terminal is brought back into service and dispatched downwardly upon closure of contact OH-3 in the circuit of relay SDA. During this down trip, the car from the upper terminal will answer any car calls or down hall calls which may be registered below it. Upon arrival at the lower terminal, the doors of the car open and reclose, closing contact DODCL in the circuit of the associated TS timer. As contact OH-5 is already closed, resistor 80 is connected across terminals 81, 82, reducing the timing period from 6 minutes to a much shorter time, as 25 seconds. At the end of this period, the motor generator set for the car not in service is again shut down.

Off-hours operation may be terminated in response to a demand for service in the system. Each time the off-hours service car leaves the lower terminal floor, timer TOH begins to operate. If the car in service has not returned within a predetermined time, TOH completes its cycle and opens contact TOH, breaking the holding circuit for relay OHS. This operation is accomplished in the following manner. Timer TOH is connected across power lines 76, 77. It begins its period of timing upon closure of contact TOHI associated with

relay TOHI which is energized upon the departure from the lower terminal of the selected car, closing contact LTZ-*a*6 or LTZ-*b*6, completing the circuit through contact OHS-*a*3 or OHS-*b*3. If the car returns within the timing period of the timer, contact TOHI reopens and the timer automatically resets. In a specific system, the period of timer TOH is such that it permits the selected off-hours service car to travel from the lower terminal to the upper terminal and return, with two stops en route. If a call for service is registered at the lower terminal while the inservice car is away from the terminal, the operating time for timer TOH is materially reduced. The registration of the hall call at the lower terminal results in closing contact UB which connects potentiometer 87 across terminals 88, 89. Potentiometer 87 may be adjusted to provide a shortened timing period of 25 seconds, for example.

Upon termination of the off-hours service, both cars return to operation and answer calls as they may be registered until the demand for service again drops and off-hours service is reinitiated.

It will be recalled that the car from the upper terminal is returned to the lower terminal where its doors open and reclose, upon initiation of the off-hours operation. If someone at the lower terminal should enter this car during the period that the doors are open and register a car call, off-hours service is immediately terminated so this car can respond to the call. Contact OH-6 and car call contacts CCU-*a*, CCD-*a*, CCU-*b* and CCD-*b* provide an instantaneous time-out circuit for timer TOH. The OHS-4 contact for the car selected for off-hours service is open so that car calls in that car do not affect the operation of the timer. A further interlock is provided through contacts LTZ-*a*7 and LTZ-*b*7 so that car calls registered in the car returning to park at the lower terminal at the initiation of the off-hours service will not have an effect. Under these conditions, however, if a car call is registered in the car which is not designated for off-hours service and which is located at the lower terminal, the associated contact CCU or CCD closes, depending upon the direction desired by the car call. This connects a circuit across terminals 88 and 89 which times out timer TOH instantaneously. The car in which this call is registered can then restart and answer the call.

If the load switch in the car selected for off-hours service should be actuated, contact LS-4 in the holding circuit for relay OHS opens, terminating off-hours service and permitting the other car to aid in handling the service demand.

The standby car parked at the lower terminal is prevented from being selected as next up during the off-hours service so that it will not open its doors while the car providing service is away from the lower terminal answering calls; provided that other conditions as previously described have not caused the off-hours service to terminate. This can be seen by referring to the next up relay NU-*a* for car *a* and assuming that car *a* is the standby car, and car *b* is the car providing off-hours service. The next up relay NU-*a* for car *a* can not be energized when car *b* departs from the lower terminal and causes contact NU-*b* 1 to close. Although contact PL is closed for car *a*, contacts OH-4 and OHS-*a*5 both will be open to prevent energization of relay NU**a.

The foregoing detailed description is given for clearness of understanding only and no unnecessary limitations should be understood therefrom, as modifications will be obvious to those skilled in the art.

We claim:

1. In an elevator system having:
a shaftway serving a plurality of floors including a bottom terminal floor, several intermediate floors, and a top terminal floor,
a plurality of elevator cars in said shaftway to serve said floors,
means for dispatching each of said cars from either terminal floor on trips up and down said shaftway at a predetermined terminal time after a selected occurrence, including separate timing means for each terminal floor,
a door at each of said plurality of floors for access to each of said cars,

- call means at each floor and within each car for registering calls for service,
- means responsive to operation of the call means for causing each car to stop on up trips and on down trips at any intermediate floor as to which a call for service is registered which requires travel in the direction the car is moving, and
- door operating means associated with each car for opening and then closing the door at each floor at which the elevator stops,
- the improvement which comprises:
- means for balancing against one another the total of all door open time on up trips and on down trips; and
  - means for adjusting the terminal time at a terminal floor in response to an imbalance between up door open time and down door open time, to establish a shorter time at the terminal toward which traveling cars have an excess of door open time, than at the other terminal, to compensate for such imbalance and maintain substantially equal spacing among cars in the system.
2. The system of claim 1 which includes means providing a comparison time interval during which the up trip door open times and down trip door open times are continuously balanced against one another, and dispatch control means operable at the end of the comparison time interval to adjust the terminal time.
3. The system of claim 2 which includes means for adjusting the comparison interval.
4. The system of claim 1 in which the adjusting means includes means for adjusting terminal time in increments, and in which the number of increments of adjustment applied at any one time is proportional to the degree of imbalance then existing between up door open time and down door open time.
5. The system of claim 4 in which an excess of up door open time reduces the terminal time at the top terminal.
6. The system of claim 4 in which an excess of down door open time reduces the terminal time at the bottom terminal.
7. The system of claim 1 which in addition includes means

- for determining the total demand for service in both directions, and means responsive to a maximum level of total demand for reducing the terminal time equally at both terminals.
5. 8. The system of claim 7 in which the means for determining the total demand comprises means for measuring the total number of up and down calls in simultaneous registration from the call means at all the floors.
9. The system of claim 7 in which the adjusting means is arranged to adjust terminal time at either terminal from the normal terminal time and also from the reduced terminal time, toward zero.
10. The system of claim 1 which includes means responsive to the opening of a door at an intermediate floor for producing cyclic pulses until the door closes, means for continuously balancing pulses produced during up door open time against pulses produced during down door open time, and dispatch control means operable at the end of an established comparison time interval to adjust terminal time at either of the terminal floors.
11. The system of claim 10 which includes means for adjusting the time between pulses.
12. The system of claim 2 wherein said dispatch control means includes first and second means for adjusting the terminal time, each responsive to said comparison time interval means for alternately balancing up trip and down trip door open times and adjusting said terminal time, said first means balancing the door open time while the second means controls the terminal time, and the second means balancing the door open time while the first means controls the terminal time.
13. The system of claim 12 including an electronic dispatching timer and circuit means having a plurality of portions for establishing different terminal times, said first and second terminal time and adjusting means including first and second multiple switching means, actuatable from position to position to balance the door open times and to select the corresponding circuit means portion to establish the time of said electronic dispatching timer.
